UNITED STATES PATENT OFFICE.

HENRY BEZER, OF ARLINGTON, NEW JERSEY.

HIGHWAY-CROSSING PROTECTION.

Application filed August 28, 1918. Serial No. 251,861.

To all whom it may concern:

Be it known that I, HENRY BEZER, a subject of the Crown of Great Britain, and a resident of Arlington, county of Hudson, State of New Jersey, have invented certain new and useful Improvements in Highway-Crossing Protection, of which the following is a specification, reference being had to the accompanying drawings.

This invention relates to signaling, and more especially to that type of signal known as a highway crossing signal; and has, for its principal objects, certainty of operation, reliability of operation, simplicity of construction, signal indications which the users of the highway will readily understand, and the same signal for night as for day.

The signal, suitably located at the crossing of a highway, gives warning to those on the highway whether or not it is safe to go over the highway crossing. When not safe warning is given by a prominent sign Stop and a gong is sounded, when safe the sign Go is given. These signs are electrically controlled.

The sign Stop is given by force of gravity, the sign Go by generated power.

I will now particularly describe the circuits and apparatus illustrated by the accompanying drawings and embodying my invention, and will thereafter point out my invention in claims.

Fig. 1 shows a front and end elevation of the signal.

Figs. 2 and 2^a show the signal circuits for a double track railway in diagrammatic form.

Fig. 3 is a front elevation of the casing containing the signs Stop and Go. To more plainly show the parts within the casing the letters of the signs are outlined, but it will be understood that the letters are preferably white with a black background as shown in Fig. 1.

Fig. 4 is an end elevation of the casing and signs.

Fig. 5 is a plan view embracing all the mechanisms and casings therefor. The cover for the box 11, containing the motor, gears, etc., is not shown; and the top of the casing 13 containing the signal actuating mecha-

nism is shown sufficiently cut away to expose the mechanisms and electrical connections.

Fig. 6 is an elevation for clearer illustration of the mechanism for sounding the gong.

Figs. 7, 8 and 9 are elevations for clearer illustration of the mechanism which actuates the signal.

In the construction of the signal and apparatus a rotary electric motor M (see Figs. 5, 7 and 9) is shown as the driving means whereby the mechanism is actuated. The motor is mounted on a headed bar m. The head 30 of the bar m is secured to the box 11, the threaded end of the bar m engages a part projecting from and solid with the casing of the motor. Screws o, p, engage the sides of the motor and are adjusted to perfectly gear pinion P with the wheel F, as shown in Figs. 5, 7. There is access to the brush holder 17 on the left hand side of the motor, and by withdrawing the screw p only the motor can be swung over for access to the other brush holder. As shown in Figs. 5, 7, the motor is connected by reducing gears to the actuating shaft J; this reducing gear comprising a pinion P fixed on the motor shaft meshing with an intermediate gear F fixed on the shaft 10, and a pinion G fixed on the shaft 10 meshing with a gear H fixed on the shaft J.

The shaft J is suitably mounted on bearings in the casing 11. The intermediate shaft 10 is mounted between centres fixed in the casing 11, the center 14 being adjustable. To a stud on an actuating arm N secured to the shaft J is pivotally connected one end of a connecting rod O, the other end of which is pivotally connected to the cross lever A. This end of the rod O is slightly slotted, the purpose of which will be herein-after described. The cross lever A, pivotally connected at one end as aforesaid to the connecting rod O, is pivotally connected at the other end to the actuating rod A¹, and is fulcrumed upon the clutch lever L being pivoted by the pivot 13 at the upper end of such clutch-lever, and the clutch-lever is pivotally mounted upon a pin S secured to and projecting from the casing 11. Thus the clutch-lever L has a stationary

pivotal point while the pivot or fulcrum for the cross-lever A is carried by the clutch-lever L and movable thereon. The clutch-lever has secured at its lower end the armature 12 of the holding clutch electro-magnet C. The pivot or fulcrum of the cross lever A is in proximity to the stationary pivotal center of the clutch-lever L, while the clutch-armature 12 is at a considerable distance 5 from the pivotal center of the clutch-lever, thereby giving a great advantage of leverage to the pull of the clutch electro-magnet. Further, the direction of the downward thrust or resistance of the actuating rod A¹ 10 is only slightly oblique to the center line of the clutch-lever pivot and cross-lever pivot. In consequence of this construction a comparatively small magnetic attraction of the holding clutch magnet C will hold the clutch 15 locked against a considerable resistance to upward movement of the actuating rod A¹. In the event however of de-energization of the clutch-magnet C, the weight of the frame I pulling upon the lever AA and 20 therefore upon the rod A¹ and cross lever A will move the clutch armature 12 away from its magnet C and the movable pivot or fulcrum of the cross-lever A downwardly, independently of the main or actuating shaft 25 J, so as to permit the indicating means to go to danger by force of gravity. Further, when the shaft J and arm N thereon force the connecting rod O and the cross-lever A to the position shown in Fig. 8 the clutch 30 armature 12 is brought to the clutch magnet C, and if the magnet is energized the armature is held by the magnet against downward movement of the arm N, and connecting rod O, and consequently against 35 upward movement by means of the cross-lever A of the connecting rod A¹, the lever AA, and the frame I to which is attached the signal indications. It will be noted that the casing 11 is bolted to the casing 13 and 40 that the back of the casing 13 allows the parts to which stress is imparted to be secured to the casing 11 only. A portion of the bearing for the shaft J is of sufficient diameter for the bearing to be secured to 45 the casing 11 with 3 screws, likewise the head of the bar m. There is also clearance for the stud S, which is the pivot for the clutch-lever L, allowing the stud to be bolted to the casing 11 only. Also a clearance 50 55 hole for the motor wires through both casings. Each end of the casing 11, measured from the bottom of the casing to within half an inch of the top, is of a thickness and width that when faced the following parts 60 can be suitably and accurately secured thereto. At that end of the box which is bolted to a corresponding faced portion of the back of the casing 13 a bearing for the shaft J, a center for the shaft 10, the head of the bar 65 m, and the stud S for the clutch-lever L.

At the other end of the casing 11 the opposite bearing for the shaft J, the opposite center for the shaft 10, the bearing Y for a shaft to one end of which is pinned the lever R to the other end the gong hammer U, 70 also the stud for the gong W.

The casing 13 is bolted as shown to the wedge shaped casing 24. The lid of the casing 24 is curtained to surround and be sufficiently below the top of the sides and 75 ends of the casing to prevent inroad of snow or rain, as neither would run up the inner wall of the curtain.

The casting which is the base of the casing 24 has a continuous rib 25 just within the sides and ends of the casing, and high enough to enclose a soft mat upon which the frame I drops. This rib is also a rain protector for the mat and the frame I, as water would not run up the outer wall of 80 the rib. Each side of the casing 24 has an opening suitably covered by a window through which the signs are visible. As shown in Figs. 3, 4, for danger Stop would be visible, Go hidden for each approach 85 to the crossing, for safety the respective signs Go would be visible and the respective signs Stop hidden. The sides of the casing 24 have cast upon them a framing 26 sufficiently projecting therefrom to receive the 90 loosely fitting window.

It will suffice to describe the framing and window for one side only. The width of the top and sides of the framing is half an inch. Secured thereto is an outer framing 100 27. This is one inch wide. The opening in the side of the casing provides that when the window is slid upwards into required position there is half an inch of window extending beyond the top, sides, and bottom 105 of the said opening. The window is further kept in place by a removable bar 28 supported by the turned in ends of the framing 27 as shown in Figs. 3, 4. Water streaming down upon or beating against the 110 window would not run up the glass which extends beyond and surrounds the opening in the side of the casing 24. The bar 28 is not thick enough to be a ledge or projection upon which snow could build up to obscure 115 the window, snow has an uninterrupted fall to earth. The lantern 16, (shown in Fig. 1), is of a type commonly used in railway signaling.

It has a $\frac{1}{8}$ oil fed wick and an oil well 120 with sufficient oil to make it a 5 day lantern. Each side of the lantern has a red, or other colored bull's eye 32, to give warning at night of approach to the crossing. This sign is visible from a distance but 125 when at near approach to the crossing the traveller would be guided by the illuminated lettered sign indication. The front eye of the lantern is preferably white, has a suitable reflector and is within the aperture Z 130

in the broad end of the casing 24 shown in Fig. 4.

As shown in Fig. 1 but not in Fig. 4 the broad end of the casing 24 is cast with a stand 33 for the lantern. To this is fastened a 2 inch width of angle iron, and secured thereto by a sufficiently loose bolt or rivet 34 is one end of a flat spring Q. The curled end of the spring bears against the back of the lantern forcing the front face of the lantern against the metal surrounding the aperture Z in the broad end of the casing 24.

This prevents inroad of snow or rain. By pulling upon the spring Q at its curled end it turns upon the slack bolt or rivet and is out of the way for removal and replacement of the lantern.

A two chambered balanced movable wedge shaped frame I is shown in Figs. 3, 4, 5. Signs Stop and Go are formed on a sheet of thin white celluloid by the surface outside of the letters being painted black, thereby providing a black background with white letters. The sign Stop encloses each side of the upper chamber of the frame I, the sign Go each side of the lower chamber, thereby indicating the traffic conditions for each highway approach to the crossing. The letters show white by day and are illuminated at night by the beams from the white eye of the lantern 16 which, as before described, is within the aperture Z. It will be seen that the respective signs are brought into line with the light, Stop by force of gravity, Go by force of generated power. In addition to the signs Stop and Go, to give warning by day of approach to the crossing I provide a fixed sign 15, (see Fig. 1), which can be of any preferred design. This sign is visible from a distance.

As before described the side bull's eye of the lantern gives similar warning at night.

The lettered signs are legible by night and by day at near approach to the crossing.

It may be that this combination of signals may induce motorists to slow down when approaching a crossing.

The signs are at an angle to the line of the light sufficient to ensure equal illumination of all the letters. The light is reflected from the top, bottom, and narrow end of the respective chambers, which surfaces are painted with white enamel paint.

The gong W, shown in Figs. 1, 5, 6, 8, is sounded by power of the motor M, which by revolving the main shaft J causes the toothed cam K fixed to the shaft J to operate the bell-hammer U. A shaft 35 having fixed at one end the lever R and at its other end the bell-hammer U turns within the bearing Y screwed to the casing 11.

As the shaft J revolves, each passing tooth of the cam K operates the lever R causing

it to strain upon the spring V. With the passing of a tooth the spring V strains upon the lever R conveying movement to the bell hammer U and sounding the gong W. The spring V can be adjusted by the screw X to produce rebounding blows and thereby a pleasant sounding gong. The bearing Y is screwed to the casing 11, that part of the shaft for the lever R and the lever R which is within the casing 11 is protected from rain or snow by the lid for the casing.

A collar Y¹ is solid with and formed upon the bearing Y, similarly protecting that part of the shaft and the hammer U which is within the gong W, as water would not run up the wall of the collar Y¹. By this formation of the bearing Y the gong can be exposed and give an unmuffled sound.

I will now describe the operation of the signal mechanism in the giving of the various indications and circuits therefor.

A closed track circuit is most commonly employed as a means for controlling a railway highway crossing signal. Such a circuit is shown in Figs. 2 and 2^a for a double track railway.

Across one end of the section of trackway for the rails 6, 7, separated by insulated rail joints from the track in rear and advance of the section, a battery 18 is connected. Across the other end is connected the track relay T. The battery, the rails, and the relay together form the well known closed track circuit. The track circuit for approach to the crossing by the other track is not described as it is in all respects similar to that for rails 6, 7. Fig. 2 shows a train 19 just within the block or trackway section for the rails 6, 7, and by bridging the said rails causes in the well-known manner the de-energization of the relay T and consequent drop of its armature, thereby opening at contact f the following circuit for the clutch coils C, which was closed prior to the entry of the train as shown in Fig. 2^a. From battery B¹ by wire 3, motor M, wire 2, contact g in relay T¹, thence by wire 8 to contact f, thence by wire 4, coils C, wire 5 back to battery B¹. The coils C being de-energized by the opening of contact f in relay T, (as shown in Fig. 2), the signal can go to danger and display the sign Stop by force of gravity; and, as shown in Figs. 1, 3, 4. The signs Go are hidden.

Then the actuating mechanism would be in positions shown in Fig. 7, owing to the downward thrust caused by the weight of the frame I, the lever AA, the rod A¹ and the lever A bearing upon the fulcrum for the lever A upon the clutch lever L, causing upward movement of the lever L and the armature 12 away from the clutch magnet C. As the circuit closer E is no longer held clear of the closer E¹ by the adjustable screw

D in the manner shown in Figs. 2^a and 9, E contacts with E¹ and the following circuit is completed for the motor M, see Fig. 2. From the battery B by wire 1, circuit closers 5 E, E¹, wire 2, motor M, wire 3 back to battery B. The shaft J now revolves in direction of the arrow shown in Fig. 6.

One half revolution of the shaft J places the arm N link O and lever A in positions 10 shown in Fig. 8, and by the lift of the lever A the clutch lever L is moved down until the armature 12 lightly contacts with cores of the clutch coils C.

By a further half revolution of the shaft 15 J there would be a downward movement of the lever A and an upward movement of the lever L into positions shown in Fig. 7 and these movements would continue until the train 19 was clear of the track section for 20 rails 6, 7, and the gong W would be sounded by the revolution of the cam K fixed to the shaft J as hereinbefore described.

As the lever A is only lifted at the end to which is pivotally connected the link O the 25 stop signs are stationary and the circuit closers E, E¹ remain closed. With the train past the crossing as shown in Fig. 2^a, or by any other avenue for its departure from the rails 6, 7, the battery 18 would energize the 30 relay T and contact f would be closed. The following circuit for the clutch coils C is then completed as shown in Fig. 2^a, but it will be understood that the circuit closers E, E¹ remain closed until opened by the 35 screw D as shown in Fig. 9, and also that until then the motor is energized by battery B. From battery B by wire 1, circuit closers E, E¹, wire 2 to contact g in relay T¹, thence by wire 8 to contact f in relay T, thence by 40 wire 4, clutch coils C, wire 5 back to battery B¹. It will be seen that for this circuit for the coils C the batteries B and B¹ are in series thereby putting additional holding power in the clutch coils C while the load is 45 being lifted to change the signs from Stop to Go. The clutch coils C being energized when, as before described, the clutch-lever L is moved down by the revolution of the shaft J and the armature 12 is placed to the cores 50 of the coils C as shown in Fig. 8 the coils hold the armature and lever L. The fulcrum for the cross lever A is then rigid and by the further revolution of the shaft J the lever A is moved to the position shown in 55 Fig. 9, the consequent pull of the rod A¹ upon the lever AA, (as shown in Figure 3), raises the frame I until the sign Go appears and the sign Stop is hidden.

The motor circuit is opened at the circuit 60 closers E, E¹, by the screw D as shown in Fig. 9 and diagrammatically in Fig. 2^a, the sign Go is held in the required position by the clutch coils C, and the gong is silent. By the adjustment of the screw D the motor

circuit would be opened and exhaust its 65 momentum to bring the arm N on the shaft J on practically a dead centre, and by this means the frame I is held and Go displayed by the power of the clutch magnet C only. The hole for the pivotal connection of the 70 link O with the lever A is slightly slotted in manner and extent sufficient for the armature 12 to be against the cores of the clutch coils C before the link O has completed its upward thrust upon the lever A. With the 75 actuating mechanism in positions shown in Fig. 9 the clutch coils C lose the power of the battery B, but the coils hold the armature 12 and lever L by the already described circuit for the battery B¹ only shown in 80 Fig. 2^a.

As before described all movable parts are 85 enclosed and weather proof and therefore the force of gravity can be depended upon, but some might opine that residual magnetism in the coils C might hold the load. In such event with the motor energized by a 90 circuit now to be described and the parts remaining in positions shown in Fig. 9 owing to failure of gravity action, the thrust 95 of the link O would force the lever A to positions shown in Fig. 8 and therefore forcibly produce the sign Stop. The motor would then have circuit via E, E¹, in multiple with that to be described and by which 100 the sign Stop was forcibly displayed. The first half revolution of the shaft J would force display of the sign Stop, further revolution of the shaft J would include the 105 weight or resistance of the frame I, the lever AA, the rod A¹, and the lever A to bear upon the fulcrum for the lever A on the clutch-lever L. Applicant assumes that residual 110 magnetism in the clutch-coils C would not overcome this pressure, and therefore the frame I having been forced down the sign Stop would continue given and the gong 115 would be sounded. I will now describe this additional circuit for the motor. Fig. 2 shows a back contact h in relay T¹ and a back contact L in relay T this latter contact closed because the train 19 bridges the rails 6, 7. A wire connects contact h to contact L to which is attached the wire 1. Should 120 there be trains to both approaches to the crossing contacts h and L would contact with the wire 1 and as owing to failure of gravity action the circuit closers E, E¹ would be open there would be the following circuit for the motor by which as before described the sign Stop would be forcibly given. From battery B by wire 1 contact h in relay T¹, closed because it has been assumed that a 125 train is on the track section for the relay T¹, thence by wire 2, motor M, wire 3, back to battery B. There would be the same circuit if only the contact h in the relay T¹ were closed, but as the figure only shows a

train 19 bridging the rails 6, 7, the circuit for the motor to forcibly display the sign Stop is: From battery B by wire 1 contact L in relay T contact *g* in relay T¹, wire 2, 5 motor M, wire 3 back to battery.

It is evident that various modifications other than those shown and described may be made in the construction and arrangement of the various circuits and apparatus 10 within the scope and spirit of my invention.

What I claim and desire to secure by Letters Patent, is:—

1. In a highway crossing signal, indicating means biased to indicate danger comprising a movable wedge shaped frame having an upper and lower chamber, the narrow end of the frame closed the wide end open, the sides of the chambers being of transparent material, each side of the upper chamber having a danger indication and each side of the lower chamber having a safety indication, actuating mechanism therefor, the bias of the indicating means producing the danger indication and hiding 20 the safety indication by force of gravity independently of the actuating mechanism, the danger indication changed by the actuating mechanism to the safety indication and hiding the danger indication by force 25 of generated power, means whereby the actuating mechanism will forcibly display the danger indication independent of the force of gravity, and means at the open end of the frame illuminating the signal indications to render the signal visible at night 30 as by day.

2. In a highway crossing signal, in combination: indicating means biased to indicate danger comprising a movable wedge shaped frame having an upper and lower chamber, the narrow end of the frame closed the wide end open, the sides of the chambers being of transparent material, each side of the upper chamber having a danger indication each side of the lower chamber having a safety indication, actuating mechanism therefor, a clutch controlling the movement to safety and safety indication and including a pivoted clutch-lever co-acting with a retaining and releasing part and a cross lever fulcrumed on the clutch lever and connected to the actuating mechanism and the signal indicating means, the biased indicating means being 45 free to swing the clutch-lever on its pivot and display the danger indication by force of gravity independently of the actuating mechanism when the clutch-lever is released, and the actuating mechanism controlling the clutch-lever through the cross-lever to swing the clutch-lever into engaging position with the retaining and releasing part, and means whereby the actuating mechanism controls the signal indicating means through the cross-lever to force the 50

display of the danger indication independent of the force of gravity.

3. In a highway crossing signal, in combination: indicating means biased to indicate danger comprising a movable wedge shaped frame having an upper and lower chamber, each side of the upper chamber having a danger indication each side of the lower chamber having a safety indication, means for hiding the safety indication when the danger indication is given and for hiding the danger indication when the safety indication is given, means for actuating the indicating means and a clutch controlling the movement to safety and safety indication and comprising a pivoted clutch lever and a stationary retaining and releasing part therefor, the means for actuating the signal being held by the clutch lever in operative condition to put the signal indicating means to safety when the clutch lever is held by the stationary part, the signal indicating means being free by force of gravity to swing the clutch lever away from the stationary part and go to danger independently of the actuating mechanism when the clutch lever is not held by the stationary part and the actuating means controlling the clutch-lever to swing the clutch lever into engaging position relatively to the stationary part, and means whereby the actuating means controls the signal indicating means to force the display of the danger indication independent of the force of gravity. 100

4. In a highway crossing signal, in combination: indicating means biased to indicate danger comprising a movable wedge shaped frame having an upper and lower chamber, each side of the upper chamber having a danger indication each side of the lower chamber having a safety indication, means for hiding the safety indication when the danger indication is given and for hiding the danger indication when the safety indication is given, means for actuating the indicating means, an actuating part for the actuating mechanism, a pivoted clutch lever carrying an armature located at a distance from the pivot of the clutch lever and a clutch electromagnet co-operating with such armature, a cross-lever fulcrumed on the clutch-lever in proximity to the pivot of the clutch-lever, a connecting rod pivotally connected to the cross-lever and connecting the same with the actuating part, and an actuating rod pivotally connected to the cross lever and connecting the cross-lever with the signal indicating means, with the direction of thrust caused by the weight of the signal indicating means upon the cross lever and its fulcrum on the clutch lever nearly in line with a line drawn through the pivotal center of the clutch lever and the pivotal center of the part carrying 110 115 120 125 130

the armature and pivotally connected to the clutch lever.

5. In a highway crossing signal, in combination: indicating means biased to indicate danger comprising a movable wedge shaped frame having an upper and lower chamber, the sides of the chambers of transparent material, each side of the upper chamber having a danger indication and each side of 10 the lower chamber having a safety indication, actuating mechanism therefor, a clutch controlling the movement to safety and safety indication and including a pivoted clutch-lever carrying an armature co-acting 15 with a stationary retaining and releasing clutch electromagnet, and a cross-lever fulcrumed on the clutch-lever and connected to the actuating mechanism and the signal indicating means, the biased indicating means 20 being free to swing the clutch-lever on its pivot by force of gravity and display the danger indication hiding the safety indication independently of the actuating mechanism when the clutch-lever is released, and 25 the actuating mechanism controlling the clutch-lever through the cross-lever to swing the clutch-lever and armature into engaging position with the clutch electromagnet and if held by the magnet the actuating mechanism 30 will operate to put the signal indicating means to safety hiding the danger indication, an electric motor for operating the actuating mechanism, a circuit for said motor, a source of current included in said 35 circuit, a circuit controller in said circuit normally open but closed by the signal indicating means moving to indicate danger by force of gravity, a normally closed circuit for the stationary clutch electromagnet, 40 a source of current included in said circuit, means connecting the motor to the actuating mechanism whereby operation of the motor places the clutch lever and armature to the clutch electromagnet, the actuating mechanism 45 then in operative condition and with the clutch magnet energized continued operation of the motor moves the signal indicating means to safety, means controlled by the cross-lever for opening the circuit for the 50 motor whereby further movement of the signal indicating means ceases and they are held in position to indicate safety by the clutch-magnet and means for controlling the circuit for the clutch-magnet.
55. 6. In a signal, indicating means biased to indicate danger, means comprising a motor and a magnetic clutch co-operating with the signal whereby said signal is moved to safety position and is held by said magnetic 60 clutch in safety position, a power supply for the motor, a power supply for the magnetic clutch, means whereby both power supplies are connected in series to energize the magnetic clutch for the movement of the signal to safety position and means whereby the

first power supply is discontinued from the magnetic clutch when the signal arrives at the safety position.

7. In a highway crossing signal, indicating means biased to indicate danger comprising a movable wedge shaped frame having an upper and lower chamber, the narrow end of the frame closed the wide end open, the sides of the chambers of transparent material, each side of the upper chamber 75 having a danger indication each side of the lower chamber having a safety indication, side stationary means allowing movement of the wedge shaped frame for display of the required indication, an opening in each 80 said side stationary means, only the required indication visible through said opening, a stationary lantern located at the wide end of the wedge shaped frame whereby the indications are at an angle to the direction of the lantern's rays, the end, top and bottom of each chamber coated with white enamel paint, actuating mechanism placing the safety indication in line with the light, the danger indication placed in line with the light by force of gravity independently of the actuating mechanism and means whereby the actuating mechanism will forcibly 85 display the danger indication independent 90 of the force of gravity. 95

8. In a highway crossing signal, indicating means biased to indicate danger including a movable wedge shaped frame having an upper and lower chamber, the narrow end of the frame closed the wide end open, the sides of the chambers of transparent material, each side of the upper chamber having a danger indication each side of the lower chamber having a safety indication, 100 a wedge shaped casing enclosing but allowing movement of the wedge shaped frame for display of the required indication, an opening in each side of the wedge shaped casing, only the required indication visible through said opening, a lantern located at the wide end of the wedge shaped casing, an aperture in said wide end for entry of the lantern's rays, whereby the indications are at an angle to the direction of the lantern's rays, the end, top and bottom of each 105 chamber of the wedge shaped frame coated with white enamel paint, actuating mechanism placing the safety indication in line with the light the danger indication placed 110 in line with the light by force of gravity independently of the actuating mechanism, means whereby the actuating mechanism will forcibly display the danger indication 115 independent of the force of gravity. 120

9. In a highway crossing signal, indicating means biased to indicate danger comprising a movable wedge shaped frame having an upper and lower chamber, the narrow end of the frame closed the wide end open, the sides of the chambers being of 125

transparent material, each side of the upper chamber having a danger indication each side of the lower chamber having a safety indication, a wedge shaped casing enclosing but allowing movement of the wedge shaped frame for display of the required indication, an opening in each side of the wedge shaped casing, an outside window wider and longer than the opening, rear and front framing for the window the front framing

secured to the top and sides of the rear framing and overlapping the rear framing and the window to prevent entry of snow or rain, a removable bar support for the window slightly thicker than the window giving snow an uninterrupted fall to earth.

HENRY BEZER.
